MOVABLY INTERFITTED IRONING BOARD
AND SUPPORT THEREFOR

Alpha Perry Lantz, Washington, D. C.

Application August 28, 1947, Serial No. 771,096

9 Claims. (Cl. 38—129)

1

This invention relates to a novel movably interfitted ironing board and support therefor.

The invention has for its object the provision of such a combination whereby the simple loose interfitting of the ironing board between supporting walls or equivalent plates on the end walls of a cabinet will enable the board to be swung from or into the cabinet, as desired, minimizing the necessity of employing nails, screws, hinges, or appliances in such interfitting, other than integral portions of the said plate or wall and the board itself.

Another object of the invention is to further simplify the construction and arrangement of the ironing board and its supporting means, by so relating them for swinging movement that a substantially uniform depth or thickness of the board may be had throughout the length thereof, avoiding projecting portions above-and-below the planes of the upper and lower surfaces of the board, for example, as constituted by the commonly employed legs, props or braces carried by the extended or ironing portion of the board outwardly beyond the cabinet, that not only constitute obstructions below the ironing area of the board but, when attached to the board, necessitate the provision of storage space for the said legs, props or braces, securing devices therefor, etc.

A preferred embodiment of the invention comprises the making of the ironing board of wood, pulp, plastic or material of inexpensive character, at times unsuited to withstand the chipping or cracking if alone used in bearings, or stops, provided with an armor facing, for the bearing engaging portions of the board which, while not substantially increasing the normal thickness of the board, will absorb the contacting shocks and strains incident to throwing the board from closed to open position or vice versa, and thus prevent the wood or the like body from chipping or cracking, by presenting a hard, durable contact facing.

A second embodiment of the invention embraces a structure wherein the board is formed entirely throughout of sheet metal having a downwardly directed flange turned about a strong wire or rod, to add rigidity to the board and prevent any tendency of the same to be unduly depressed under ironing forces, the specific construction of the board in this embodiment being the widening of the entire inner portion of the board so that the edges thereof constitute the lateral extensions to enter and cooperate with the openings in the bearing plate on the cabinet wall, as distinguished from providing the equivalent elongated lateral extensions of the first described embodiment, where the extreme inner end of the board is relatively of less width and projects backward in the cabinet beyond the said lateral extensions.

2

The foregoing embodiments of the invention, also possess the common novel characteristic of the bearing member in the cabinet wall or the like adapted to cooperate with the bearing engaging member of the board, whether of the armored wood or other formation, comprising a plate to be secured to said wall in fixed position, with respect to the latter, having its central portion formed with oppositely arranged sector-shape openings communicating with each other at their inner converging ends and providing arc-shaped outer bearing surfaces.

Also the characteristic of a complemental lateral extension on the side edge of the board of substantially the same thickness thereof, to interfit with the openings in the plate, with the opposite ends of the extension, disposed to ride in said openings over the arc-shaped surfaces of the latter for the purpose of preventing longitudinal displacement of the board; and spaced parallel vertical and horizontal abutments located to opposite sides of the axis of the swing of the board so as to engage the upper and lower faces of the latter and limit the swing of the board upwardly or downwardly.

Still other features of novelty will be developed in a discussion of the respective disclosures, all of which will be readily understood from the detail description hereinafter contained when read in connection with the drawings forming part hereof.

In the drawings, and first with respect to the embodiment of the invention initially referred to—

Figure 1 is a vertical sectional view of a portion of a cabinet in which the ironing board is mounted;

Figure 2 is a transverse section of Figure 1 on the line X—X of the latter;

Figure 3 is a top view of the ironing board of Figure 2;

Figure 4 is an end view looking in the direction of the arrow of Figure 1; and

Figure 5 is a vertical section on the line Y—Y of Figure 1 looking in the same direction.

Figure 6 is a side view of the plate of Figure 1, certain details being eliminated.

Figure 7 is a view of the same character as Figure 1, showing the second embodiment of the invention;

Figure 8 is a vertical section on the line Z—Z of Figure 7 looking in the direction of the arrow;

Figure 9 is a top plan view of the inner end of the ironing board of Figure 7; and

Figure 10 is a bottom view of the same.

Figure 11 is a fragmentary section of a cabinet provided with a somewhat different shaped open bearing portion receiving and constituting abutments for engaging the lateral extensions of and limiting the movements of the board; and

60

Figure 12 is a vertical section of Figure 11 on the line A—A thereof, viewed in the direction of the arrow.

Referring more specifically to the drawings, and first with reference to that embodiment illustrated in the first six figures thereof, 15 represents the back wall, and 16 the side or end walls of a cabinet, here but fragmentarily shown. On each end wall of the cabinet and disposed on the inner face thereof, there is a sheet metal plate 17 secured by screws 18, this plate having oppositely disposed sector-shaped openings 19 and 20 therethrough registering with corresponding openings in the side walls 16, the plate 17 having a continuous outwardly turned flange 21 closely fitted to the opening, represented at 22, in the wall 16.

The openings 19 and 20 through the plate 17 are curved, as an arc-shape, as shown at 23 (in the instance of the opening 19) and 24 (in the instance of the opening 20), and the flange 21 is correspondingly contoured to provide bearing surfaces, as will later appear.

The inner or relatively smaller end portions of the sector-shape openings 19 and 20 open to each other to afford communication between the openings 19 and 20 at what I will term the axis 25 (Figure 6) of swinging movement of the ironing board 26. The arrangement of the openings 19 and 20, with respect to each other, and the continuous outwardly turned flange 21 thereof, is such that the portions of the flanges constituting the ends of the openings 19 and 20, serve as stops or abutments for the board in its various positions. The stops or abutments are in pairs at right angles to each other and are, in one pair, horizontally disposed as shown at 27 and 28 (Figure 1) in planes spaced apart the thickness or depth of the board 26; and in the other pair arranged vertically in planes and spaced the same way, the stops or abutments being there illustrated at 29 and 30. This arrangement permits the board to occupy a horizontal or ironing position, (full lines Figure 1) or a closed vertical position (dotted lines same figure).

The plate 17 is also provided with pressed or struck-out auxiliary stops 31 and 32 serving in connection with the bearings or abutments, constituted by the shaping of the flange 21, bordering the openings 19 and 20, to afford abundant support for the ironing board under severe or abnormal pressure or forces on the ironing portion of the board when extended from the cabinet.

The board 26 of Figure 1 may be of any suitable material, for example, relatively soft or cheap wood, or other substance, if deemed expedient, but it being the object of the invention to have the same capable of supporting itself when inter-engaged with the open portions 19-20 of the plate 17 and be also capable of resisting fracture, cracking or the like when engaging the bearing portions thereof, the board, in this instance, is provided with an armor of sheet metal. This armor comprises a bottom plate 33 adapted to extend transversely across the under face of the board 26, where the latter projects into the cabinet, and upwardly around the side edges of the board at 34 and over onto the upper surface of the board, as at 35, the plate and board being permanently secured together in fixed relationship by rivets or the like 36. This metal protection for the wood will absorb the shocks incident to the abutment of the board with the

bearing parts in the plate 17, and preserve the wood from chipping or cracking.

The inner end of the board, that is, the end that remains in the cabinet when the ironing portion of the board is extended beyond the cabinet, is of the form illustrated in plane in Figure 3, it being understood that the integral board extends into, and is of the same shape, as the armor 34-35, providing elongated or oblong edge extensions projected beyond the normal edge 26a of the board to interfit with the bearing portions of the plate 17, the ends 38 of these oblong portions being arranged to engage and ride over the curved end surfaces or flanges 23 and 24 of the sector-shape openings 19 and 20 of the plate 17. The only difference between the plate 17 of Figure 1 and of Figure 6 is that the auxiliary stops 31 and 32 of the form of Figure 1 is dispensed with in Figure 6.

Now, with reference to that embodiment illustrated in Figures 7 to 10, inclusive, it is seen that in lieu of being formed of wood, as suggested in Figure 1, the board in this instance, is formed entirely of sheet metal, but the general combination and arrangement remains about the same as that already described.

Here the back wall of the cabinet is represented at 39, the end wall thereof at 40 and the plate on the inner face of the end wall at 41, secured thereto at 42, as before. The bearing plate 41 has the outwardly turned flange 43 fitting the corresponding opening 44 in the end wall 40 of the cabinet, said flange 43 and opening 44 in the cabinet being constituted, as in the preceding embodiment, by the sector-shape portions 45 and 46 of the plate providing the pairs of stops or abutments 47 and 48 (of the horizontal arrangement) and the similar stops (of vertical arrangement) 49 and 50. As before, the open portions 45 and 46 meet at their smaller ends to communicate in permitting the swinging of the board up-and-down about an axial portion 51. The board, represented in this instance at 52, is formed entirely of sheet metal with a substantially flat upper surface throughout, save for an ironing implement seat 53, formed by an appropriately depressed portion of the material of the board near the inner end thereof. The surrounding edge of the board throughout has a depending flange 54 folded tightly about a wire or rod marginal reinforce 55 to stiffen and reinforce the board during the function of ironing thereon. It is thus seen that the board again is of substantially uniform depth or thickness throughout, the same as in the instance of the embodiment of the first series of figures, and is without hooks, projecting parts, etc., above-and-below the board.

The shape of the inner end or head of the board—that is the portion that in its movement remains in the cabinet—is substantially broadened relative to the normal width 57 of the ironing portion of the board. This broadened portion or head of the board is indicated at 58 and the extended side edges of the head, shown at 59 enables the broad itself to constitute the oblong bearing engaging portions equivalent to the bearing engaging portions 37 of the first embodiment, it being understood that the edge portions 59 extend into the open portions 45 and 46 of the plate 41 (Figure 7) into position to have the edge 60 of the head 58, ride upon the curved or arc surface 61 of the open portion 45, and the end surface 62 of the head to ride over the cor-

responding arc-shaped surface 63 of the open portion 46.

In the arrangement just described, the edge projecting portions 59 at the head of the board extend to the extreme end 62 of the board. No stops (as 31 Figure 1) are provided in this instance, but to afford ample support for strenuous ironing operations a stop 64 is formed with the plate 41 for the outwardly projecting portion of the board, the same as in the instance of 32 in Figure 1.

The outwardly extending portions of the board, of the suggested normal width 57 of Figure 10 and 26a of Figure 3, are of less width than the inner end of the board having the edge extensions for engaging the bearings in the end plates and the intermediate portion 65, the edge of which rides on the plate 41 in the up-and-down movement of the board, so that room is provided for a covering sheet or padding on the ironing portion of the board without liability of said padding projecting outwardly beyond the edge 65 in position to have closing movement of the board obstructed by the front edge of the side wall 48 of the cabinet.

In Figures 11 and 12 the opening in the end plate, here shown as at 66, is varied in contour as compared to the openings of Figures 1 and 7. The opening in this instance is of approximately circular formation 67, in its lower portion, opening to a relatively shallow space 68, bordered by an upper curved or arc-shaped flange 69. Spaced relatively top and bottom stops 70 and 71 are struck out from the plate 66, as will be understood from a knowledge of the preceding constructions. The parallel stops or abutments of the two sets, inherent in the two preceding abutments, are in the instance under discussion constituted in the novel manner of utilizing one end 72 of the open portion 68, as one abutment of the horizontal pair, the other being constituted by a struck-out shoulder portion 73, from the flange 74, fitting the corresponding opening 75 of the end wall of the cabinet. The other pair of abutments or stops (the vertical pair) are constituted by the opposite end wall 76 of the open portion 68, there being a like struck-out shoulder 77.

In the use of the device shown in Figure 11 the ironing board will take the position indicated in full lines at 78 when horizontal and operative, and the vertical position shown by dotted lines, when closed or in inoperative position, the relative spacing of the stops and shoulders being that to accommodate the depth of the board, in either of its two positions, as will be appreciated.

The board to be used with this special form of Figure 11 may be of either the type shown in Figure 1 or Figure 9.

I claim:

1. An ironing board of the character described formed of an integral piece of material having lateral integral projections adjacent to one of its ends and extending a substantial distance longitudinally of the ironing board, in combination with bearings in the end walls of a cabinet, each bearing being formed by communicating sector shaped openings bound by straight walls providing abutments and curved walls providing bearing surfaces, the curved walls being diametrically spaced substantially the length of one of the projections of the ironing board with which they engage, the interengagement of the projections with the bearing surfaces forming the pivot for the ironing board and maintaining the same against longitudinal displacement, said ironing board projections being adapted to engage the abutments afforded by the straight walls when the ironing board is swung outwardly to ironing position or upwardly to inoperative position.

board projections being adapted to engage the abutments afforded by the straight walls when the ironing board is swung outwardly to ironing position or upwardly to inoperative position.

5 2. An ironing board of the character described formed of an integral piece of material having lateral integral projections adjacent to one of its ends and extending a substantial distance longitudinally of the ironing board, in combination with bearings in the end walls of a cabinet, each bearing being formed by communicating sector shaped openings bound by straight walls providing abutments and curved walls providing bearing surfaces, the curved walls being diametrically spaced substantially the length of one of the projections of the ironing board with which they engage, the interengagement of the projections with the bearing surfaces forming the pivot for the ironing board and maintaining the same against longitudinal displacement, said ironing board projections being adapted to engage the abutments afforded by the straight walls when the ironing board is swung outwardly to ironing position or upwardly to inoperative position, said bearings having associated therewith auxiliary abutment means adapted to be engaged by the ironing board.

15 3. A combination including supporting plates adapted to be secured to the end walls of a cabinet and an ironing board having laterally extending integral extensions elongated lengthwise of the board, each plate having upper and lower communicating openings therein of general sector shape bound by straight and curved walls, the 20 curved wall of each opening being arcuate shaped and forming part of a bearing, the straight walls of each opening providing abutments for limiting the swinging movement of the ironing board, said arcuate shaped bearing walls of each plate 25 being diametrically spaced substantially the length of one of the extensions of the ironing board with which they engage, the interengagement of the extensions with the arcuate shaped bearing walls forming the pivot for the ironing board and maintaining the same against longitudinal displacement, said ironing board extensions being adapted to engage the abutments afforded by the straight walls when the ironing board is swung outwardly to ironing position or upwardly to inoperative position.

30 4. A combination including supporting plates adapted to be secured to the end walls of a cabinet and an ironing board having laterally extending integral extensions elongated lengthwise of the board, each plate having upper and lower 35 communicating openings therein of general sector shape bound by straight and curved walls, the curved wall of each opening being arcuate shaped and forming part of a bearing, the straight walls of each opening providing abutments for 40 limiting the swinging movement of the ironing board, said arcuate shaped bearing walls of each plate being diametrically spaced substantially the length of one of the extensions of the ironing board with which they engage, the interengagement of the extensions with the arcuate shaped bearing walls forming the pivot for the ironing board and maintaining the same against longitudinal displacement, said ironing board extensions being adapted to engage the abutments afforded by the straight walls when the ironing board is swung outwardly to ironing position or upwardly to inoperative position, said ironing board extensions having reinforcing means to shield the same at the points of contact with the 45 abutments.

5. A combination including supporting plates adapted to be secured to the end walls of a cabinet and an ironing board having laterally extending integral extensions elongated lengthwise of the board, each plate having upper and lower communicating openings therein of general sector shape bound by straight and curved walls, the curved wall of each opening being arcuate shaped and forming part of a bearing, the straight walls of each opening providing abutments for limiting the swinging movement of the ironing board, said arcuate shaped bearing walls of each plate being diametrically spaced substantially the length of one of the extensions of the ironing board with which they engage, the interengagement of the extensions with the arcuate shaped bearing walls forming the pivot for the ironing board and maintaining the same against longitudinal displacement, said ironing board extensions being adapted to engage the abutments afforded by the straight walls when the ironing board is swung outwardly to ironing position or upwardly to inoperative position, each of said supporting plates including an auxiliary abutment adjacent its forward edge adapted to be engaged by the ironing board, comprising a projection extending inwardly of the plate.

6. A combination including supporting plates adapted to be secured to the end walls of a cabinet and an ironing board having laterally extending integral extensions elongated lengthwise of the board, each plate having upper and lower openings therein of general sector shape, each opening being bound by two walls perpendicular to each other and an arcuate shaped bearing wall connecting the perpendicular walls, the perpendicular walls of one opening being so connected to the perpendicular walls of the other opening as to allow communication between the upper and lower openings to provide a space for the accommodation of one of the laterally extending integral extensions of the ironing board, said laterally extending integral extensions engaging the arcuate-shaped bearing walls, forming a pivot means for the ironing board, said extensions also adapted to engage the perpendicular walls, the latter constituting abutments for the extensions when the ironing board is swung outwardly to ironing position or upwardly to inoperative position.

7. A combination including supporting plates adapted to be secured to the end walls of a cabinet and an ironing board having laterally extending integral extensions elongated lengthwise of the board, each plate having upper and lower openings therein of general sector shape, each opening being bound by two walls perpendicular to each other and an arcuate shaped bearing wall connecting the perpendicular walls, the perpendicular walls of one opening being so connected to the perpendicular walls of the other opening as to allow communication between the upper and lower openings to provide a space for the accommodation of one of the laterally extending integral extensions of the ironing board, said laterally extending integral extensions engaging the arcuate shaped bearing walls, forming a pivot means for the ironing board, said extensions also adapted to engage the perpendicular walls, the latter constituting abutments for the extensions when the ironing board is swung outwardly to ironing position or upwardly to inoperative position, the ironing board and extensions being of substantially the same depth or thickness throughout

and the extensions of the ironing board having reinforcing means consisting of a sheet metal protective facing adapted to contact said abutments.

8. A combination including supporting plates adapted to be secured to the end walls of a cabinet and an ironing board having laterally extending integral extensions at the end of the board and elongated lengthwise of the board, each plate having upper and lower communicating opening therein of general sector shape bound by straight and curved walls, the curved wall of each opening being arcuate shaped and forming part of a bearing, the straight walls of each opening providing abutments for limiting the swinging movement of the ironing board, said arcuate shaped bearing walls of each plate being diametrically spaced substantially the length of one of the extensions of the ironing board with which they engage, the interengagement of the extensions with the arcuate shaped bearing walls forming the pivot for the ironing board and maintaining the same against longitudinal displacement, said ironing board extensions being adapted to engage the abutments afforded by the straight walls when the ironing board is swung outwardly to ironing position or upwardly to inoperative position, said ironing board and extensions being formed of sheet metal and having reinforcing means in the form of beaded marginal portions.

9. A combination including supporting plates adapted to be secured to the end walls of a cabinet and an ironing board having laterally extending integral extensions elongated lengthwise of the ironing board, each plate having upper and lower communicating opening therein of general sector shape bound by straight and curved walls, the walls extending outwardly from the plate through cut-out portions in the side walls of the cabinet, the curved wall of each opening being arcuate shaped and forming part of a bearing, the straight walls of each opening providing abutments for limiting the swinging movement of the ironing board, said arcuate shaped bearing walls of each plate being diametrically spaced substantially the length of one of the extensions of the ironing board with which they engage, the interengagement of the extensions with the arcuate shaped bearing walls forming the pivot for the ironing board and maintaining the same against longitudinal displacement, said ironing board extensions being adapted to engage the abutments afforded by the straight walls when the ironing board is swung outwardly to ironing position or upwardly to inoperative position.
